RAILWAY TRAFFIC CONTROLLING APPARATUS

Melvin A. Penrod, Murrysville, Pa., assignor to
The Union Switch & Signal Company, Swiss-
vale, Pa., a corporation of Pennsylvania

Application March 26, 1930, Serial No. 438,995
Renewed June 8, 1932

11 Claims. (Cl. 246—3)

My invention relates to railway traffic controlling apparatus, and particularly to apparatus for controlling traffic governing devices, such as railway track switches, by levers which are located at a central point such as an interlocking tower.

One feature of my invention is the provision of means for controlling the movement of a switch in accordance with traffic conditions in advance of the switch.

I will describe two forms of apparatus embodying my invention, and will then point out the novel features thereof in claims.

In the accompanying drawing, Fig. 1 is a diagrammatic view illustrating one form of apparatus embodying my invention. Fig. 2 is a similar view showing a modified form of a portion of the apparatus of Fig. 1, and also embodying my invention.

Similar reference characters refer to similar parts in both views.

Referring first to Fig. 1 of the drawing, the reference characters 1 and 1^a designate the track rails of a stretch of railway track X, which is divided, by means of insulated joints 2, into a plurality of track sections A—B, B—C and C—D. A second track Y is connected with the track X by means of a switch G located in section B—C, and the rails 1^b and 1^c thereof are divided, by insulated joints 3, to form a section E—F. Each of the sections A—B, B—C, C—D and E—F is provided with a track circuit which is supplied with current by a track battery 4 connected across the rails adjacent one end of the section, and which includes a track relay, designated by the reference character R having a distinguishing exponent corresponding to its location, connected across the rails adjacent the opposite end of the section. The section of the track Y between the point F and the switch G is included in the track circuit of the section B—C by a conductor 5 connecting the rails 1 and 1^c of the tracks X and Y, respectively.

The entrance of a westbound train into the section C—D is controlled by a signal S¹ and by an automatic train stopping device 6, and its movement over the switch G is controlled by signals S^{2a} and S^{2b}. In a like manner the movement of a westbound train from the section A—B of the main track X or from the section E—F of the track Y is controlled by signals S³ and S⁴, respectively. Also, the movement of an eastbound train over the switch G from the section A—B of the track X or from the section E—F of the

track Y is controlled by the usual dwarf signals S⁵ and S⁶, respectively.

Switch G is controlled by an operating mechanism J which is in turn controlled by a manually operable lever V¹ which is located at a remote point, such as an interlocking tower, and which is movable between a normal position n, indicated by full lines in the drawing, and a reverse position r, indicated by broken lines in this view. The lever V¹ operates an arm 7 which engages a contact 7^a when the lever occupies its normal or n position and a contact 7^b when the lever occupies its reverse or r position. The lever V¹ also operates an arm 8 which engages a contact 8^a when the lever occupies its normal or n position and a contact 8^b when the lever occupies its reverse or r position. By means of this lever the towerman may operate the mechanism J so as to move the switch G between its normal and reverse position. Under certain trackway conditions, hereinafter to be described, the lever V¹ will be locked in its normal position by a latch 9 cooperating with a locking segment 10 and under certain other trackway conditions this lever will be locked in its reverse position by a latch 11 cooperating with a locking segment 12. The segments 10 and 12 are both mounted on the same shaft on which the lever V¹ is mounted, which shaft may constitute part of an interlocking machine of the usual type, and the latches 9 and 11 are operated to engage and disengage the segments by a lock magnet L which is controlled by a control relay K.

The signal S¹ and the train stopping device 6 are controlled by a lever V², which may be located in the interlocking tower, through the medium of a relay T, and also by a circuit controller H comprising a contact 13—14 closed at all times except when the switch G occupies its reverse position, and a contact 13—15 closed at all times except when the switch occupies its normal position. The lever V² moves between a normal position n and a reverse position r and operates a contact 16, a contact 17 and a slow-acting contact 18. When the lever V² occupies its normal position n, in which it is illustrated in the drawing, contact 16 is open, the contact 17 is closed, and the slow-acting contact 18 is also closed. When, however, the lever V² is moved to its reverse position r, contact 16 is closed, and contacts 17 and 18 are opened. The slow-acting contact 18 is of the type that opens quickly when the lever V² is moved to its reverse position but requires a predetermined interval of time after the lever V² is returned to its normal position

before this contact is closed. One form of device which may be used to operate this contact is disclosed in Letters Patent of the United States No. 1,157,960, granted to H. B. Post on October 5 26, 1915. When levers V^1 and V^2 both occupy their n positions and relay R^4 is energized, the control relay K is energized by current traversing three different circuits thereby maintaining its contacts 19 and 20 closed. Current in the first 10 of these circuits flows from terminal x of a suitable source of electrical energy not shown in the drawing, through contact 8-8^a of lever V^1 , front contact 21 of track relay R^4 , and winding of relay K to the other terminal o of the same source. Current in the second of these circuits flows from terminal x , through slow-acting contact 18 of lever V^2 , and winding of relay K to terminal o . The third circuit is a stick circuit for the control relay K through which current 15 flows from terminal x , through contact 17 of lever V^2 , contact 19 of control relay K , and the winding of this relay to terminal o . As hereinbefore mentioned, the energization of the relay K maintains the contact 20 thereof closed, and 20 consequently the lock magnet L will be energized by current flowing from terminal x , through a front contact 22 of track relay R^2 , contact 20 of control relay K , and winding of lock magnet L to terminal o . The energization 25 of magnet L maintains the latches 9 and 11 out of engagement with the segments 10 and 12, thereby permitting operation of the switch lever V^1 to its reverse position should the towerman desire to reverse the switch G .

30 35 I will now assume that the towerman desires to move the signal S^1 to its "clear" position, and the automatic train stopping device 6 to an ineffective position in order to allow a westbound through train to pass over the track X . Under 40 such circumstances he swings the signal lever V^2 to the right, as viewed in Fig. 1, to its reverse position r , thereby opening the contacts 17 and 18 and closing the contact 16. The opening of the contacts 17 and 18 breaks the circuits through 45 these contacts which energized the relay K jointly with the circuit through the contact 8-8^a of the lever V^1 but inasmuch as contact 8-8^a of lever V^1 is closed, the circuit for relay K through this contact remains closed and as a consequence 50 the relay K remains energized. The closing of the contact 16 by the above-described movement of the lever V^2 establishes a circuit from the terminal x through contact 16 of lever V^2 , front contact 23 of track relay R^1 , contact 14-13 of 55 circuit controller H , front contact 24 of track relay R^2 , front contact 25 of track relay R^3 , and winding of relay T to terminal o . The current in this circuit energizes the relay T and causes it to close its front contacts 26 and 27 and establish 60 two separate circuits. Current in the first of these circuits flows from terminal x , through contact 26 of relay T , and the operating mechanism of signal S^1 to terminal o , thereby causing the signal S^1 to assume its "clear" position. The 65 current in the second of these circuits flows from terminal x , through contact 27 of relay T and the mechanism of the automatic train stopping device 6 to terminal o , and causes the device 6 to assume its ineffective position.

70 75 As the train enters the section C-D from the east the track relay R^3 is deenergized, thereby releasing its front contact 25, and breaking the circuit previously traced through the relay T thus causing this relay to become deenergized. 75 This causes the signal S^1 to again display a stop

indication to succeeding trains. The deenergization of track relay R^3 also causes a contact 28 thereof to close and to establish a circuit from terminal x , through back contact 28 of track relay R^3 , contact 29, and operating mechanism 80 of the automatic train stopping device 6 to terminal o . Contact 29 is closed when the section to the right of point D is occupied, and the circuit just traced therefore prevents device 6 from resuming its normal effective position while the train 85 occupies both section C-D and the section to the right of this section.

As soon as the train enters section E-C, the track relay R^2 becomes deenergized and opens its front contacts 22 and 24. The opening of the contact 22 breaks the circuit previously traced, which maintains the lock magnet L energized and causes the release of the latches 9 and 11. The notch in the segment 10, being in registry 90 with the latch 9 at this time is engaged thereby and prevents the leverman from operating the lever V^1 to reverse the switch G while the train is passing over the switch and as long as it occupies the section E-C.

When the train leaves section C-D the track relay R^3 becomes reenergized and closes its contact 25 but by reason of the fact that the contact 24 of relay R^2 is now open the circuit through the relay T remains open and the signal S^1 continues to display a "stop" indication. The energization of track relay R^3 also opens its contact 28 thereby opening the circuit previously traced through this contact and the contact 29 which maintains the automatic train stopping device to route a westbound train from the track X to the track Y. He, therefore, swings the switch lever V¹ to the right to its *r* position, thereby opening the contact 7-7^a and closing the contact 5 7-7^b. The closing of contact 7-7^b causes the energization of the switch operating mechanism J and moves the switch G to its reverse position. The above described movement of the lever V also opens the contact 8-8^a and closes the contact 10 8-8^b. The opening of the contact 8-8^a breaks the circuit through this contact, the contact 21 of track R⁴, and the winding of relay K, but the stick circuit through the contact 17 of lever V² and the circuit through the slow-acting contact 18 remain 15 intact, so that relay K remains energized. The closing of the contact 8-8^b establishes an additional circuit for the relay K through front contact 30 of track relay R¹. The movement of the switch G from its normal to its reverse position 20 opens contact 13-14 and closes contact 13-15 of the circuit controller H.

The towerman now swings the lever V² to its reverse or *r* position thereby closing its contact 16 and opening both of its other contacts 17 and 25 18. The closing of contact 16 establishes a circuit from terminal *x* through contact 16 of lever V², front contact 31 of track relay R⁴, contact 13-15 of circuit controller, front contact 24 of track relay R², front contact 25 of track relay R³, 30 and winding of relay T to terminal *o*. The energization of this relay closes its contacts 26 and 27 and causes the signal S¹ to display a "clear" indication and the automatic train stopping device 6 to assume an ineffective position as hereinbefore described. The opening of contacts 17 and 18 of lever V² breaks the circuits through these contacts which energizes the control relay K leaving this relay energized by the additional circuit hereinbefore traced through the contact 8-8^b 40 of lever V¹ and front contact 30 of track relay R¹.

When a westbound train enters section C-D the track relay R³ becomes deenergized. This opens front contact 25, and deenergizes relay T with the result that the contacts 26 and 27 thereof 45 open and interrupt the circuits therethrough. The result of this is that the signal S¹ is caused to again display a "stop" indication but the train stopping device 6 is maintained in its ineffective position by the circuit through back contact 28 50 of relay R³ and contact 29.

Upon the entry of the train into section B-C the track relay R² becomes deenergized and opens its front contacts 24 and 22. The opening of contact 22 causes deenergization of lock relay L and permits its latch 11 to move into locking engagement with the associated segment 12, thereby preventing the switch lever V¹ from being operated to return the switch G to normal as long as any portion of the train occupies section B-C. As the 55 train departs from section C-D the track relay R³ again becomes energized and closes its front contact 25 and opens its back contact 28, but by reason of the fact that the contact 24 of the track relay R² is open, the circuit through the relay T is held open. The opening of the contact 28 breaks the circuit that holds the device 6 ineffective and therefore this device resumes its normal operative position for succeeding trains.

The train next proceeds over the switch G and enters section E-F of track Y immediately causing the deenergization of track relay R⁴. As the train departs from section B-C the track relay R² again becomes energized and closes its contacts 24 and 22 but inasmuch as the front contact 31 75 of relay R⁴ is now open, the circuit for relay T

is held open. The signal S¹ therefore remains at "stop". The closing of contact 22 of track relay R², however, reestablishes the circuit through the lock magnet L and causes it to move the latch 11 out of engagement with the segment 12. The lever V¹ may now be operated to return the switch to normal if so desired.

It will be noted that the switch lever V¹ is locked against movement so that it is impossible to return the switch G to its normal position, as long as the train occupies section B-C, but that as soon as the train departs entirely from section B-C the track relay R² again becomes energized and reestablishes the circuit through the lock magnet L. As a result of this arrangement the operator may return the switch to normal and the signal S¹ to "clear" as soon as a train leaves the section B-C in which the switch is located even though the train still occupies section E-F of track Y.

My system also includes means for preventing the switch G from being moved from normal to reverse after a westbound train has entered section C-D upon a "clear" indication of the signal S¹ and the possibility of derailment occasioned thereby. For example, I will assume that section E-F of track Y is occupied by a westbound train and that the switch G has been returned to its normal position and the signal S¹ displays a clear indication for westbound traffic over track X. Under these conditions I will also assume that another westbound train enters section C-D and that the towerman desires for some reason to switch the second train onto the track Y occupied by the first train. The switch G is however locked in its normal position by reason of the fact that the contacts 17, 19, 18 and 21, which independently control the energization of lock magnet L are all open. The towerman can not close contact 21 because the track relay R⁴ which controls this contact is deenergized due to the presence of the first train in section E-F. He can not cause the energization of the lock magnet L by closing contact 17 because the contact 19 in this stick circuit is open due to the deenergization of the magnet K. The towerman, therefore, must first return the signal lever V² to its normal position thereby releasing the slow-closing contact 18. The time interval of this contact is

of sufficient duration to permit the second train to pass the switch entirely if it is a fast moving train that does not have time to stop before crossing the switch or if although having sufficient time to stop, disregards the signal. The time interval is, however, of sufficient duration to permit the train to come to a complete stop before it reaches the switch G if the engineer of the westbound train obeys the signal S^{2a} and is not running at too great a speed. If the second train stops before reaching the switch G the circuit through contact 18 will be established at the expiration of the time interval and the control relay K will be energized and close contact 20, thereby causing the energization of the lock magnet L, as previously described. This will cause the release of the switch lever V¹ and permit the towerman to move the switch G to its reverse position. The second train may then proceed onto the track Y at reduced speed.

I will now assume that an eastbound train is approaching section E-F of track Y and that the switch G occupies its normal position and that the signal S¹ displays a clear indication for westbound trains over the track X. Under such conditions the control relay K is energized only by

current in the circuit controlled by contact 21 of track relay R^4 and contact 8-8^a of switch lever V^1 . Consequently, if the eastbound train should enter section E-F before the towerman reverses 5 the switch G, the track relay R^4 already having become deenergized and opened its front contact 21, relay K will have become deenergized and opened its front contact 20, thereby deenergizing the lock magnet L and preventing the subsequent operation of the switch lever V^1 . Also, if 10 the towerman should first move the signal lever V^2 to its normal position in order to cause the signal S^1 to display a "stop" indication to westbound traffic, the slow-acting contact 18 might 15 not close before the eastbound train enters section E-F. As a result the control relay K would become deenergized and cause the switch lever V^1 to be locked in its normal position as above described.

20 I avoid the above mentioned difficulty by the provision of the stick circuit controlled by the contact 17 of the signal lever V^2 and the contact 19 of the control relay K. By means of this circuit the towerman can prevent the deenergization 25 of the relay K if he moves the signal lever V^2 to its normal position and thereby closes the contact 17, while the relay K is still energized by current traversing the circuit controlled by the contacts 7 and 21. If the eastbound train now 30 enters section E-F and deenergizes the track relay R^4 , the control relay K will not become deenergized through the delayed closing of slow-acting contact 18. The switch lever V^1 is therefore maintained in an unlocked condition thereby 35 permitting the towerman to move the switch G to normal at his convenience.

In Figure 2 I have shown another form of my 40 invention for delaying the energization of the control relay K and the unlocking of the switch G when it is desired to reverse the switch while the section E-F is occupied. In this arrangement the slow-acting contact 18 shown in Fig. 1 is omitted and a contact 32 operated by a slow pick-up relay M substituted therefor. The relay 45 M is controlled by a contact 33 operated by track relay R^3 and is provided with a second contact 34 which is closed only when the relay M is deenergized and which is interposed in the signal circuit between the circuit controller H and the contact 24 of track relay R^2 . In all other particulars the arrangement shown in Fig. 2 is the 50 same as that disclosed in Fig. 1 and therefore much of the corresponding apparatus has been omitted from the drawing. With the arrangement 55 above described I will again assume that the section E-F is occupied, that the switch G is in its normal position, and that the signal S^1 displays a "clear" indication to westbound traffic over track X.

60 If a westbound train now enters section C-D the track relay R^3 will become deenergized and open its front contact 25, thereby breaking the signal circuit and causing the signal S^1 to display a "stop" indication to succeeding trains, as hereinbefore described. The deenergization of track relay R^3 also closes its back contact 33, thereby completing a circuit from terminal x through contact 33 and winding of slow pick-up relay M to terminal o. This causes the energization 65 of slow pick-up relay M but by reason of its slow-acting characteristics it will not close its contact 32 until the expiration of a predetermined time interval. As a result, the circuit through this contact 32 which controls the energization of control relay K is not immediately

established and the contact 20 controlled by this relay remains open. This prevents the immediate energization of the lock relay L and maintains the switch G locked in its normal position until the expiration of the time interval required for the slow pick-up relay M to close its contact 80 32. As in the case of the slow-acting contact 18 in the system shown in Fig. 1, this time interval is of sufficient duration to permit the westbound train to pass entirely over the switch G before the switch actuating mechanism is unlocked, thereby eliminating the danger of moving the switch beneath the train in the event that the towerman should make a sudden decision to reverse the switch without giving the train sufficient time to stop or in the event that the train should disregard the signal and proceed over the switch.

If, however, the towerman decides in due time to route the train onto track Y for some reason, he first actuates the signals S^{2a} and S^{2b} by means forming no part of my present invention to indicate such fact in time to permit the train to stop before reaching the switch G. At the expiration of the time interval after deenergization 100 of relay R^3 above mentioned the contact 32 of the slow pick-up relay M closes, thereby completing a circuit through the control relay K. The energization of control relay K causes the contact 20 controlled thereby to close and to complete the circuit previously traced through the lock magnet L. This causes the energization of the lock magnet and causes it to elevate the latch 9 out of engagement with its associated locking segment 10 and release the switch lever V^1 . The 110 towerman may now operate the lever V^1 to reverse the switch as hereinbefore described.

From the foregoing it will be apparent that I have provided a very simple and convenient apparatus for controlling the operation of a track 115 switch in accordance with the condition of the track both in front of and beyond the switch whereby the danger of moving a switch beneath a train is to a large extent eliminated.

Although I have herein shown and described 120 only two forms of apparatus embodying my invention, it is understood that various changes and modifications may be made therein within the scope of the appended claims without departing from the spirit and scope of my invention.

Having thus described my invention, what I claim is:

1. In combination, a plurality of tracks each divided into a plurality of sections, a track switch located in one of said sections for connecting said tracks, switch operating means for moving said switch between normal and reverse positions, a lever for controlling said operating means, lock mechanism for controlling the operation of said lever, electromagnetic means for controlling the operation of said lock mechanism, a control relay for controlling the operation of said electromagnetic means, a first contact adapted to be closed when said lever is moved to a normal position for controlling said control relay, a second contact adapted to be closed when said lever is moved to a reverse position for controlling said control relay jointly with said first contact, a track relay associated with one of said sections of one of said tracks for controlling said control relay jointly with said first contact, a track relay associated with one of said sections of another of said tracks for controlling said control relay jointly with said second contact, and means 130 135 140 145 150

for at times controlling said control relay independently of said first and second contacts and said track relays.

2. In combination, a plurality of tracks each divided into a plurality of sections, a track switch located in one of said sections for connecting said tracks, switch operating means for moving said switch between normal and reverse positions, a lever for controlling said operating means, lock mechanism for controlling the operation of said lever, electromagnetic means for controlling the operation of said lock mechanism, a control relay for controlling the operation of said electromagnetic means, a first contact adapted to be closed when said lever is moved to a normal position for controlling said control relay, a second contact adapted to be closed when said lever is moved to a reverse position for controlling said control relay jointly with said first contact, a track relay associated with one of said sections of one of said tracks for controlling said control relay jointly with said first contact, a track relay associated with one of said sections of another of said tracks for controlling said control relay jointly with said second contact, and a stick circuit including a third contact for at times controlling said control relay independently of said first and second contacts and said track relays.

3. In combination, a plurality of tracks each divided into a plurality of sections, a track switch located in one of said sections for connecting said tracks, switch operating means for moving said switch between normal and reverse positions, a lever for controlling said operating means, lock mechanism for controlling the operation of said lever, electromagnetic means for controlling the operation of said lock mechanism, a control relay for controlling the operation of said electromagnetic means, a first contact adapted to be closed when said lever is moved to a normal position for controlling said control relay, a second contact adapted to be closed when said lever is moved to a reverse position for controlling said control relay jointly with said first contact, a track relay associated with one of said sections of one of said tracks for controlling said control relay jointly with said first contact, a track relay associated with one of said sections of another of said tracks for controlling said control relay jointly with said second contact, a signal for controlling traffic over said tracks, signal controlling means for causing said signal to display "clear" and "stop" indications, and a third contact adapted to be operated when said signal controlling means is operated for controlling said control relay independently of said first and second contacts and said track relays.

4. In combination, a plurality of tracks each divided into a plurality of sections, a track switch located in one of said sections for connecting said tracks, switch operating means for moving said switch between normal and reverse positions, a lever for controlling said operating means, lock mechanism for controlling the operation of said lever, electromagnetic means for controlling the operation of said lock mechanism, a control relay for controlling the operation of said electromagnetic means, a first contact adapted to be closed only when said lever is moved to its normal position, a second contact adapted to be closed only when said lever is moved to its reverse position, a track relay associated with one of said sections of one of said tracks on one side of said switch, a second track relay associated with another of said sections of another of said tracks on the same side of said switch, a first control circuit including said first contact and a front contact of said first track relay for controlling said control relay, a second control circuit including said second contact and a front contact of said second track relay for controlling said control relay, and a slow-acting contact for at times controlling said control relay independently of said first and second control circuits.

5. In combination, a plurality of tracks each divided into a plurality of sections, a track switch located in one of said sections for connecting said tracks, switch operating means for moving said switch between normal and reverse positions, a lever for controlling said operating means, lock mechanism for controlling the operation of said lever, electromagnetic means for controlling the operation of said lock mechanism, a control relay for controlling the operation of said electromagnetic means, a first contact adapted to be closed only when said lever is moved to its normal position, a second contact adapted to be closed only when said lever is moved to its reverse position, a track relay associated with one of said sections of one of said tracks on one side of said switch, a second track relay associated with another of said sections of another of said tracks on the same side of said switch, a first control circuit including said first contact and a front contact of said first track relay for controlling said control relay, a second control circuit including said second contact and a front contact of said second track relay for controlling said control relay, and a slow-acting contact for at times controlling said control relay independently of said first and second control circuits.

6. In combination, a plurality of tracks each divided into a plurality of sections, a track switch located in one of said sections for connecting said tracks, switch operating means for moving said switch between normal and reverse positions, a lever for controlling said operating means, lock mechanism for controlling the operation of said lever, electromagnetic means for controlling the operation of said lock mechanism, a control relay for controlling the operation of said electromagnetic means, a first contact adapted to be closed only when said lever is moved to its normal position, a second contact adapted to be closed only when said lever is moved to its reverse position, a track relay associated with one of said sections of one of said tracks on one side of said switch, a second track relay associated with another of said sections of another of said tracks on the same side of said switch, a first control circuit including said first contact and a front contact of said first track relay for controlling said control relay, a second control circuit including said second contact and a front contact of said second track relay for controlling said control relay, a signal for indicating the condition of said tracks, signal controlling means for causing said signal to display "clear" and "stop" indications, and a slow-acting contact operated by said signal controlling means for controlling said control relay independently of said first and second control circuits.

7. In combination, a railway track, a second railway track, a track switch connecting said

150

- second track with said first track and which in its normal position directs traffic movements along said first track only but which in its reverse position directs traffic movements along said first track to or from said second track, a signal for governing trains approaching said switch in the facing direction, a circuit controlled by said switch in its normal position and by traffic conditions on said first track beyond said switch for controlling said signal, a second circuit controlled by said switch in its reverse position and by traffic conditions on said second track for controlling said signal, and means for preventing an operation of said switch from one of its positions 10 to the other while said signal is controlled to indicate "proceed" if traffic conditions on that track beyond the switch to which traffic would be directed by such operation of the switch are such as to cause said signal to indicate "stop".
- 20 8. In combination, a railway track, a second railway track, a track switch connecting said second track with said first track and which in its normal position directs traffic movements along said first track only but which in its reverse position directs traffic movements along said first track to or from said second track, a signal for governing trains approaching said switch in the facing direction, a circuit controlled by said switch in its normal position and by traffic conditions on said first track beyond said switch for controlling said signal, a second circuit controlled by said switch in its reverse position and by traffic conditions on said second track for controlling said signal, and means for delaying 30 for a measured period of time an operation of said switch from one of its positions to the other if traffic conditions on that track beyond the switch to which traffic would be directed by such operation of the switch are such as to cause 40 said signal to indicate "stop".
9. In combination, a stretch of railway track comprising a switch section and a second section, a second stretch of track including a third section, a switch in said switch section connecting said second stretch with said first stretch, a switch lever having a normal and a reverse contact closed in normal and reverse positions respectively of said lever, means controlled by said lever for operating said switch to its normal position for directing traffic movements along said first stretch only or to its reverse position for directing traffic movements to or from said second stretch according as said lever is placed in its normal or its reverse position respectively, a 50 locking relay, a circuit controlled by said normal lever contact and by traffic conditions in said third section for controlling said relay, a second circuit controlled by said reverse lever contact and by traffic conditions in said second section for controlling said relay, a manually controllable slow-acting device, a third circuit controlled by said slow-acting device for controlling said relay, and means controlled by said relay for controlling said lever.
- 65 10. In combination, a stretch of railway track comprising a switch section and a second section, a second stretch of track including a third sec-
- tion, a switch in said switch section connecting said second stretch with said first stretch, a switch lever having a normal and a reverse contact closed in normal and reverse positions respectively of said lever, means controlled by said lever for operating said switch to its normal position for directing traffic movements along said first stretch only or to its reverse position for directing traffic movements to or from said second stretch according as said lever is placed in its normal or its reverse position respectively, a locking relay, a circuit controlled by said normal lever contact and by traffic conditions in said third section for controlling said relay, a second circuit controlled by said reverse lever contact and by traffic conditions in said second section for controlling said relay, a slow-acting device controlled by traffic conditions in said first stretch in the direction from said switch from which trains approach when facing said switch, a third circuit controlled by said slow-acting device for controlling said relay, and means controlled by said relay for controlling said lever.
11. In combination, a stretch of railway track comprising a switch section and a second section, a second stretch of track including a third section, a switch in said switch section connecting said second stretch with said first stretch, a switch lever having a normal and a reverse contact closed in normal and reverse positions respectively of said lever, means controlled by said lever for operating said switch to its normal position for directing traffic movements along said first stretch only or to its reverse position for directing traffic movements to or from said second stretch according as said lever is placed in its normal or its reverse position respectively, a locking relay, a circuit controlled by said normal lever contact and by traffic conditions in said third section for controlling said relay, a second circuit controlled by said reverse lever contact and by traffic conditions in said second section for controlling said relay, a signal lever having a normal and a reverse position and having a first contact which is closed if and only if its lever is in the reverse position and a second contact which is closed if and only if its lever is in the normal position as well as a third contact which becomes closed if and only if its lever has been in the normal position a measured period of time, a third circuit controlled by the third contact of said signal lever for controlling said relay, a stick circuit for controlling said relay controlled by the second contact of said signal lever, a circuit controlled by the first contact of said signal lever and by traffic conditions in said second section for controlling said signal if said switch is in its normal position, a circuit controlled by the first contact of said signal lever and by traffic conditions in said third section for controlling said signal if said switch is in its reverse position, and means controlled by said relay for controlling said switch lever.

MELVIN A. PENROD.
